Primary Examiner—Prabhakar Deshmukh(74) *Attorney, Agent, or Firm*—Pennie & Edmonds LLP(57) **CLAIM**

The ornamental design for the luggage cart, as shown and described.

DESCRIPTION

FIG. 1 is a top, front, and side perspective view of an ornamental design for a luggage cart according to the present invention;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

All portions shown in broken lines are environmental and illustrative only and form no part of the claimed design.
